UNITED STATES PATENT OFFICE.

RUFUS C. NOURSE, OF BOSTON, MASSACHUSETTS, ASSIGNOR OF ONE-HALF
TO HENRY BUDDEN, OF BOSTON, MASSACHUSETTS.

HEAD-REST FOR USE IN SHAMPOOING.

No. 853,592.

Specification of Letters Patent.

Patented May 14, 1907.

Application filed June 3, 1905. Serial No. 263,631.

To all whom it may concern:

Be it known that I, Rufus C. Nourse, a citizen of the United States, residing at Boston, county of Suffolk, and State of Massachusetts, have invented an Improvement in Head-Rests for Use in Shampooing, of which the following description, in connection with the accompanying drawings, is a specification, like letters on the drawings representing like parts.

This invention has for its object to provide a novel rest for a person's head while it is being shampooed.

The present practice is for a person being shampooed to rest his forehead on a pad which is made simply by folding up one or two towels, and which is supported on the marble slab or top of the set bowl. Such a pad, however, does not make a very steady support and a person's head is likely to slip off from it while the shampooing operation is in progress.

I have devised a novel form of head-rest which is shaped to make a firm support for the head, and which will not be uncomfortable for a person to rest his head upon.

My improved device comprises a block or rest adapted to sit on top of the marble slab of a set bowl, and shaped on its upper side to fit the forehead and cheeks of a person's head, and also shaped to present a nose-receiving recess. The result is a head-rest which is comfortable for a person to rest his head against and which makes a very firm support for the head.

In the drawings Figure 1 is a perspective view of a portion of a set bowl showing my improved head-rest in position for use; Fig. 2 is a vertical central section through the head-rest, said figure showing in dotted lines the position of the person's head when supported thereby.

3 designates any suitable or usual set bowl, and 4 the usual marble slab forming the top of the bowl.

My improved head-rest comprises a block, designated generally by 5, which is adapted to rest on the marble slab 4, and which is hollowed out on its upper side, as at 6, to conform to the general shape of a person's forehead and cheeks. Said block is also cut away, as at 7, to form a nose-receiving recess which preferably extends clear across the block. Said recess is shown as having an in-

clined bottom 8 and is of comparatively slight depth at the side of the block toward the bowl, while at the opposite side of the block said recess extends clear through the block. Said recess is also preferably slightly wider at the latter side of the block than at the opposite side, and the side walls 9 of the recess are shown as being tapered.

Any suitable means may be used for securing the head-rest in place. In some instances it may not be necessary to use any securing means, but I prefer to employ some such device. As herein shown the securing means comprises clips 10 which project from the outer side of the block and are adapted to hook over the edge of the marble slab 4 and spring holding fingers 11 which are adapted to hook over and engage the edge of the opening in the marble slab. These spring fingers and clips may bend in any suitable way. Each clip is herein shown as being integral with one spring finger, the wire which forms the clip being extended through the block, as at 12, and formed into a coil, as 13, on the inner face of the block, the wire of the coil being extended to form the holding finger 11. Preferably the holding-fingers 11 are bent at their ends, as at 14, to form hooks to engage the edge of the opening in the marble slab.

When the device is not in use the resiliency of the fingers 11 causes them to lie flat against the inner face of the head-rest. In applying said head-rest to a set-bowl the hooks 10 are hooked over the edge of the marble slab and the hooked ends of the spring holding fingers 11 are then caught over the edge of the opening in the marble slab, as shown in Figs. 1 and 2. Any other suitable way of holding the head-rest in place may be employed, however, without departing from the invention.

In using the device the person whose head is to be shampooed places his head on the rest, as shown in dotted lines Fig. 2, so that the forehead and cheeks rest on the hollowed or concaved surface 6, and the nose occupies the nose-receiving recess 7. If desired a towel or cloth may be placed over the rest to make a sort of cushion on its surface. A head-rest thus constructed is very comfortable for a person to rest his head on while being shampooed, and is also of such a shape that the head is firmly supported thus rendering it

easier for the shampooer to work. The spring fingers 11 permit the head-rest to be used on bowls which have marble slabs of different widths.

5 Various changes may be made in the construction of the device without departing from the invention.

Having described my invention what I claim as new and desire to secure by Letters 10 Patent is:—

A head-rest for shampooing, comprising a block to rest on the marble-slab of a set-bowl, said block being provided on its upper face

with a nose-receiving recess, clips projecting from one edge of the block and adapted to hook over the edge of the marble-slab, and yielding fingers projecting from the opposite edge of said block and adapted to engage the edge of the opening in said marble-slab.

In testimony whereof, I have signed my 20 name to this specification, in the presence of two subscribing witnesses.

RUFUS C. NOURSE.

Witnesses:

LOUIS C. SMITH,
HENRY BUDDEN.
